MECHANICAL PINNING DEVICE

William F. Ortiz, San Francisco, Calif.

Application May 7, 1935, Serial No. 20,301
Renewed March 17, 1936

4 Claims. (Cl. 223—110)

This invention relates to a mechanical pinning device, the general object of the invention being to provide means whereby draperies, curtains and the like can be easily and quickly pinned to a 5 table or bench without danger of the operator scratching his hand or the pins catching in the goods when the device is in inoperative position.

This invention also consists in certain other 10 features of construction and in the combination and arrangement of several parts, to be herein-after fully described, illustrated in the accompanying drawings and specifically pointed out in the appended claims.

In describing the invention in detail, reference 15 will be had to the accompanying drawings wherein like characters denote like or corresponding parts throughout the several views, and in which:—

Figure 1 is a top plan view of the device.
20 Figure 2 is a view looking through the rear edge thereof.

Figure 3 is an end view thereof.
25 Figure 4 is a front view view with the parts in lowered position.

Figure 5 is an end view with the parts in raised position.

Figure 6 is a bottom plan view with parts broken away.

In these drawings, the numeral 1 indicates an 30 elongated beam and the numeral 2 indicates a pair of aligned bars spaced from the front edge of the beam and hingedly connected thereto by the spring hinges 3, each hinge having the leaf which is connected with the bar much longer than the 35 leaf which is connected with the beam and the parts are arranged as shown in Figure 1 so that when the bar is lifted it will be a considerable distance above the beam. A pin carrying bar 4 is connected by the hinges 5 to each bar 2, these 40 hinges 5 being located under the bar. An arm 6 is connected to the outer end of each pin bar 4 and extends upwardly and a pair of brackets 7 extend upwardly from the rear part of the beam adjacent the ends thereof and a link 8 has one 45 end pivoted to the upper end of each arm 6 and its other end pivoted to the upper end of each bracket so that when a bar 2 is swung upwardly these parts 6, 7 and 8 will cause the pin bar to swing downwardly and inwardly as shown in Figure 5.

Each bar 4 has the pins 9 extending from its lower face and these pins will assume the position shown in Figure 5 when the parts are in raised position so that there is no danger of the operator injuring himself on the pins. A plate 10

is connected to the bottom of the beam 1 adjacent the front edge thereof and extends outwardly beyond the beam and has holes 11 in its front edge for receiving the points of the pins when the pin bars are in lowered position as shown in Figures 4 5 and 6. Of course, the material to be gripped is placed on the plate and then by swinging the bars downwardly the pins will grip and hold the same.

The bar 2 has a handle 12 connected thereto so that by swinging a handle rearwardly downwardly 10 the bar 2 will be lifted, as shown in Figure 5, and a spring latch 13 is carried by the beam for holding each handle in lowered position with the bars in raised position. Thus when the handle is swung 15 downwardly and rearwardly to raise a pair of bars 15 the latch will engage the handle and hold the parts in this position so that the latch must be released before the parts can be swung downwardly in the gripping position.

A straight edge 14 is connected to the lower 20 face of the beam and placed at one end of the device by a bracket 15, this straight edge acting to facilitate placing of the device in position and the bottom of the beam is formed with a pair of grooves 16 which extend longitudinally and are 25 out of alignment, the grooves extending from a substantially centrally arranged recess 17 in the bottom of the beam to the ends thereof where they communicate with notches 18 opening out through the bottom of the beam and the straight 30 edge is formed with a notch 19 which forms a continuation of the notch 18. A bar 20 is slidably arranged in each groove and has its outer 35 end bent downwardly as shown at 21 to form a clamp and this bent end carries a pin 22. A lever 23 extends into the recess 17 and is pivoted to the beam as shown at 24 and a link 25 connects the inner end of one bar 20 with the lever 23 at one 40 side of the pivot 24 and a link 26 connects the inner end of the other bar to the lever at the other side of the pivot as shown in Figure 6. A plate 27 is fastened to the underside of the beam 45 and covers the recess 17 and the grooves, and the recess 17 extends through the rear edge of the beam and the outer end of the lever 23 projects from the rear edge so that it can be readily 50 moved by hand. A yoke 28 has one end connected with the outer part of the lever and said yoke extends over a portion of the beam and then has its end bent and passed through a hole in the beam and said end forming the pivot 24. A spring 55 latch 29 is carried by the upper face of the beam for engaging the yoke 28 for holding the parts in clamping position, it being understood that by moving the bars 20 in opposite direction to place 55

the device on a table or the like and then moving the lever in an opposite direction the ends 21 will clamp the table and thus firmly support the device thereon.

- 5 As it will be seen the bars 2 and 4 are of less thickness than the beam so that when the parts are in the position shown in Figure 3 the pins 9 will act to hold an edge of the fabric in position. Then when it is desired to release the fabric 10 the handles 12 are swung downwardly under the latches so as to raise the bars and thus the pins will disengage the fabric so that the fabric can be removed and the position taken by the pins, when the parts are in raised position will prevent 15 the operator from scratching his hands by the pins.

It is thought from the foregoing description that the advantages and novel features of the invention will be readily apparent.

- 20 It is to be understood that changes may be made in the construction and in the combination and arrangement of the several parts provided that such changes fall within the scope of the appended claims.

25 What is claimed is:—

1. A device of the class described comprising a beam, a bar, spring hinges connecting the bar in spaced relation to the beam, a pin carrying bar, hinges connecting the same to the first mentioned 30 bar, the hinges being connected to the lower faces of the two bars, a handle for swinging the first mentioned bar upon its hinges and means for swinging the pin carrying bar downwardly to place the pins against the first mentioned bar as 35 the first mentioned bar is swung upwardly.

2. A device of the class described comprising a beam, a bar, spring hinges connecting the bar in spaced relation to the beam, a pin carrying bar, hinges connecting the same to the first mentioned 40 bar, the hinges being connected to the

lower faces of the two bars, a handle for swinging the first mentioned bar upon its hinges and means for swinging the pin carrying bar downwardly to place the pins against the first mentioned bar as the first mentioned bar is swung upwardly, means for clamping the beam to a table and latch means for holding the handle in position with the first mentioned bar in raised position.

3. A device of the class described comprising a beam, a bar, spring hinges connecting the bar in spaced relation to the beam, a pin carrying bar, hinges connecting the same to the first mentioned bar, the hinges being connected to the lower faces of the two bars, a handle for swinging the first mentioned bar upon its hinges and means for swinging the pin carrying bar downwardly to place the pins against the first mentioned bar as the first mentioned bar is swung upwardly, said means including a bracket on the beam, and an upwardly extending arm on the pin bar and a link pivoted to the arm and to the bracket.

4. A device of the class described comprising a beam, a bar, spring hinges connecting the bar in spaced relation to the beam, a pin carrying bar, 25 hinges connecting the same to the first mentioned bar, the hinges being connected to the lower faces of the two bars, a handle for swinging the first mentioned bar upon its hinges and means for swinging the pin carrying bar downwardly to place the pins against the first mentioned bar as the first mentioned bar is swung upwardly, said means including a bracket on the beam and an upwardly extending arm on the pin bar and a link pivoted to the arm and to the bracket, 30 a plate connected with the beam and extending forwardly and having holes in its front edge for receiving the pins.
